UNITED STATES PATENT OFFICE.

ARTEMAS WARD, JR., OF DETROIT, MICHIGAN.

DESIGN FOR AN INSTRUMENT-BOARD FOR AUTOMOBILES.

57,026.

Specification for Design.

Patented Jan. 25, 1921.

Application filed January 26, 1920. Serial No. 354,262. Term of patent 14 years.

To all whom it may concern:

Be it known that I, ARTEMAS WARD, Jr., a citizen of the United States of America, residing at Detroit, county of Wayne, and State of Michigan, have invented a new, original, and ornamental Design for an Instrument-Board for Automobiles, of which the following is a specification, reference being had to the accompanying drawings, forming part thereof.

Figure 1 is a perspective view showing the front of an automobile and an instrument board embodying my design, the latter being broken away.

Fig. 2 is a perspective view showing a part of the instrument board and the inclosing walls below the same.

Fig. 3 is a detail sectional view illustrating the inclosure and hinged lid therefor.

There is a downwardly and backwardly

inclined plate *b* extending from side to side of the body at the front and within the same and having its upper edge substantially coincident with the upper edge of the forward part of the body. The plate *b* is cut away at the center and the aperture thus formed is covered by a plate *a* bearing the various instruments and hinged to the plate *b* at *a*². Inside of the plate *b* are inclosing walls *a*³ which form a complete inclosure having a cubical form or a rectangular cross-section in both longitudinal and transverse planes for the connections and interior parts of the instruments. The plate *a* forms the cover to said inclosure.

I claim:

The ornamental design for an instrument board for automobiles, as shown.

ARTEMAS WARD, Jr.
